Clair G. Wright
BY
Arthur B. Brown
ATTORNEY

UNITED STATES PATENT OFFICE.

CLAIR G. WRIGHT, OF KANSAS CITY, MISSOURI.

WAISTBAND.

Application filed August 25, 1927. Serial No. 215,427.

My invention relates to bands for garments, and more particularly to the waist bands of track pants, underwear, pajamas, and similar garments. The objects of the invention are to provide elasticity and adjustability, to provide features that are protective to the person wearing the garment and to the elements of the device, and to eliminate the cutting of a dart from a band portion of a garment in producing fullness of the garment.

The objects are accomplished by novel structure that will be described in detail with references to the accompanying drawings wherein:

Fig. 1 is a perspective view of an athletic garment having a waist band constructed in accordance with my invention.

Fig. 2 is a cross section of a portion of a waist band in which my invention is embodied.

Fig. 3 is a detailed fragmentary perspective view of an elastic element, a part of a textile cover member being broken away the better to disclose the structure.

Referring in detail to the drawings:

1 designates a pair of track pants, the waist band 2 of which is constructed of the material of the pants and consists chiefly of a hem in the upper edge of the garment produced by the annular stitches 3. Vertical plaits 4 are provided in the belt or band area, and preferably in side positions on the garment, by gathering the material at a position where a group of plaits is to be installed and attaching an elastic element 5 to the material by rows of vertical stitching 6. The elastic element is permitted to extend in length, under expansive influence to lengthen the band, by reason of the folds or plaits of the hem or band material between the rows of stitching 6. The plaits may be folded over and pressed flat, so that extending influence will cause a partial opening of the folds.

The plaits are produced on the outer side of the garment and of the band, and the elastic element therefore is on the inner side of the band, that is, adjacent the body of the wearer, and provides a smooth surface, protecting the body from the discomfort of the folds or corrugations of the plaits.

The elastic element 5 comprises preferably a strip of gum rubber 7, and a strip of knitted fabric 8, the knitted strip being equal in length to the rubber strip, and slightly less in width. The knitted strip is disposed

adjacent the rubber strip with its wales 9 transversely arranged thereto and is attached to the rubber strip by means of edge stitching 10, to provide for stretching of the knitted fabric along the face of the rubber strip, the threads of the stitch being caught in spaced and adjacent portions of the knitted fabric between the projecting wales, or in similar manner, so that the wales are not prevented from expansion. The knitted strip is provided to protect the body of the wearer from the direct contact of the rubber, and also to protect the rubber strip from deteriorating influences, such as the heat and perspiration of the body. The textile strip also provides a smooth and unwrinkled surface for contact with the person of the wearer under all conditions of extension or contraction of the elastic element of the band.

An additional co-operating element is provided in a tape 11 for adjusting the length of the band, the tape being inserted between the garment material and the elastic element 5 and secured to the band by one of the lines of stitching 6; and the eyelets 12 constructed in the device by perforating adjacent portions of the garment hem and the elastic element, and binding each pair of aligned openings to form an eyelet. Two or more vertically disposed eyelets may serve as means, in place of stitching 6, to attach the inner portion of a plait to the elastic element. Ends of the tape may be inserted into selected eyelets to form loops or drawstrings for puckering and reducing the length of the band. The adjusting means is particularly serviceable when use has stretched the rubber, and the excess material of the plaits has been extended. When the plaits are folded, before use has extended them, they may be pressed flat to provide a relatively smooth exterior surface.

The device eliminates the necessity for a dart in the belt portion and adjacent thereto, by providing for the puckering or gathering of the material; and, by means of the novel elastic element, obviating the usual disadvantages of gathers or plaits. The gathers or plaits are feasible in the band device shown, since they are used in the service of the elastic element, and since a protective element is provided for positioning over puckered portions of the band.

What I claim and desire to secure by Letters Patent is:

1. In a garment, a waist band comprising

means forming vertical plaits in the garment material and an elastic element provided with a strip of knitted fabric attached thereto, the wales of said knitted strip disposed vertically, and the elastic element secured to the garment by the means that form said plaits.

2. In a garment, a band comprising a plaited portion of the garment and an elastic element secured to said plaited portion, and vertical stitching forming said plaits and coincidentally securing the elastic element to the plaited portion, said elastic element comprising a strip of gum rubber and an extensible textile member connected with said rubber strip.

3. A waist band comprising an extensible portion of the waist, an elastic element attached to said extensible portion, eyelets engaging the elastic element and the extensible portion and providing openings therethrough, and a tape having its median portion secured to said waist at a spaced position from said eyelets for engagement with selected eyelets to reduce the length of the band.

4. A band device for a garment, comprising

ing a portion of the garment band provided with transverse plaits, an elastic member attached to said plaited portion, said plaits being folded for reception of said elastic member, stitching coincidentally producing said plaits and attaching the elastic member to said portion, and a strip of knitted fabric attached to the elastic member by stitches engaging aligned edges of the member and the strip, said fabric strip having wales disposed parallel to said plaits.

5. A band device for a garment comprising a portion of the garment band provided with transverse plaits, an elastic member attached to said plaited portion, stitching coincidentally producing said plaits and attaching the elastic member to said portion, and a strip of knitted fabric laid on the elastic member and attached thereto by tacking engaging aligned edges of the member and the strip, said fabric strip having wales disposed parallel to said plaits, and said fabric strip positioned on the opposite side of the elastic member from the position of said plaits.

In testimony whereof I affix my signature.
CLAIR G. WRIGHT.
